CLAIM

The ornamental design of a processing cassette, as
shown and described.

DESCRIPTION

FIG. 1 is a perspective view of the processing cassette
with its halves folded over one another;
FIG. 2 is an elevational view of the processing cassette
with its halves unfolded and showing their outer faces;
FIG. 3 is a side view of the unfolded processing cas-
sette, as seen from the left of FIG. 2;

FIG. 4 and 5 are respectively bottom and top views of
the cassette with its halves folded over as in FIG. 1.

FIG. 6 is an elevational view of the processing cassette
with its halves unfolded, as in FIG. 2, but showing their
inner faces; and,

FIG. 7 is a vertical sectional view of the processing
cassette, as seen along broken lines VII—VII of FIG. 6.
